UNITED STATES PATENT OFFICE.

THOMAS DAVID CASSERLY, OF CHICAGO, ILLINOIS.

SMOKE-PREVENTING DEVICE FOR BOILERS AND FURNACES.

Application filed December 14, 1925. Serial No. 75,202.

My invention relates to boilers and furnaces and more especially to a novel smoke preventing device or means therefor.

Among the objects of the present invention are to provide novel means for supplying auxiliary air, preferably in a pre-heated state, to the combustion chamber of the furnace and more especially to the combustion space in the rear of the furnace and in back 10 of the bridge wall so as to combine and mix with the gases and products of combustion and insure complete combustion and burning thereof, whereby the fuel will be thoroughly consumed and the emission thereof from the 15 chimney in the form of black smoke eliminated, thus assuring the highest efficiency for the fuel consumed, in addition to avoiding the smoke nuisance, especially with soft coal.

Another object of the invention is to provide a smokeless boiler of the transverse vertical sectional type having front, back, and a plurality of intermediate sections with a top arched portion, depending side legs and 20 inwardly extending webs so formed that the webs of two adjacent intermediate sections are spaced to receive hollow wing arches or auxiliary atmospheric air supply boxes above a fire wall dividing the boiler into a front 25 fire box and rear combustion chamber or main front combustion chamber and rear auxiliary combustion chamber so that the products of combustion will be completely consumed, and whereby all of the intermediate sections may be made of the same pattern and yet variations in the size of the fire box and relative sizes of the fire box and combustion chamber may be obtained according 30 to the capacity required.

It is also an object of the invention to supply air to the combustion space by means of a novel construction of auxiliary air admission tube or conduit which causes a whirling action of the auxiliary air which is admitted into the combustion space over the bridge wall on opposite sides of the furnace with such direction as to insure complete mixing thereof with the burning gases from the fire box chamber of the furnace. By reason 40 of being subsequently caused to pass through a circuitous or tortuous back and forth travel, complete absorption of the heat thereof is insured, while novel means is also provided for automatically regulating the supply of auxiliary air to join with the gases and products of combustion for the purpose

of securing complete consumption of the fuel and elimination of smoke, in addition to permitting the auxiliary air to enter in proper proportion to the fuel consumption or 60 the amount of heat required under varying weather conditions and temperatures.

Other and further objects will be apparent as the description proceeds.

In the accompanying drawings, Fig. 1 is a 65 sectional side elevation of a sectional or square type of furnace or boiler equipped with my improvements.

Fig. 2 is a vertical, transverse, sectional view taken on the line 2—2 of Fig. 1. 70

Fig. 3 is a detailed sectional, perspective view of one of the hollow air inlet boxes constituting a part of the device.

Fig. 4 is a detailed sectional view of the air inlet tube or conduit, and 75

Fig. 5 is a detailed horizontal, sectional view of the air inlet box of a modified form.

Referring to the drawings in detail, a boiler 6 is shown, the same being of the sectional or square type for the purpose of 80 illustrating the application of the invention. This boiler comprises a base section 7 and a sectional or other base extension 7' horizontally arranged, and a series of vertical sections including a front section 8, intermediate hollow-arched sections 9, and a rear section 10 which is closed at the back, double-walled and hollow like the front section 8, as indicated at 11. All of the sections are 85 hollow to provide water and steam-containing chambers 12. The front section 8 is provided with a fuel supply or fire door 13 and an ashpit door 14 is provided therebelow, communicating with the ashpit 15 beneath the grates 16, through which the primary supply of air and oxygen to support combustion 90 passes, over which is the firebox 17.

In most instances, the grates terminate short of the rear section of the furnace and a bridge wall or baffle 18, preferably of fire-brick is provided on the base extension 7' in back of the front base section 7 and extending transversely across the same between the depending legs of two of the sections 9, resting on a support of either solid metal plate 100 or masonry and supported at the back by a metal member 19 extending transversely across and fastened to the base support of the bridge wall, as clearly shown in Figs. 1 and 2 of the drawings, and terminating about 105 midway of the height of the fire box or chamber 17 in rear of the fire box to block off and

limit the length of the latter from the rear combustion chamber or space. The bridge wall 18 is backed up by the metallic angular reinforcing web or brace 19 which also keeps 5 the wall and firebrick in place. Under ordinary circumstances the gases and products of combustion from the fuel on the grate 16 and in the firebox 17 pass rearwardly in the combustion chamber at and to the back of the 10 furnace, and then upwardly in front of the rear section wall 11. At this point the gases are divided and pass forwardly through the outer flue openings or passes 20 to the front of the furnace or boiler; then the fire travel 15 is continued from the front of the boiler rearwardly through the inner flue openings or passes 21, to the rear of the boiler and uptake to the chimney or stack. All of the sections, as previously explained, are hollow for 20 receiving the water to be heated and circulated in a hot-water heating system or generated into steam, in a steam-heating system. The various sections are joined in airtight connection at their abutting faces 22, as indicated 25 at 23.

It will be noted that the intermediate sections 9 have depending hollow water legs at the sides and are provided with hollow-arched ribs or drop webs 24 below the flues 30 20 and 21, extending from near the bottom of the depending water leg on one side in a curved form across and over the fire box or chamber, bridge wall, and combustion chamber to near the bottom of the depending leg 35 on the opposite side so as to form a water-cooled curtain in each section, but especially at the center of the firebox and combustion chamber over the firebox. The front of the flues or passes 20 and 21 are provided with 40 cleanout doors 25. The webs 24 are so positioned as to lie on opposite sides; that is, at the front and back of the bridge wall 18, so that hollow wing arches or air boxes 26 may be fitted between pairs of webs within 45 the opposite sides of the sections or outer portions thereof, thus causing the cooling of the hollow arches by means of contact with a pair of webs containing water. Owing to the wide differences in the temperatures of 50 these parts, the sections and webs or ribs absorb the heat of the wing arches or boxes, which is transferred to the water to give greater heating efficiency, while resting upon the bridge wall 18 and providing an intermediate 55 passage or combustion space 27 therebetween forming a mixing port below the webs 24 equal to or less in cross-sectional area than either sets of flues 20 or 21, as shown, to insure proper combustion. The size and 60 position of the hollow wing arches or air boxes 26 may be made as desired and their inward extension or adjustment regulated to give the proper size to the port or space 27. Also, the hollow wing arches or air boxes 26 may 65 be moved in or out and any suitable means

employed to fill the spaces between the outer sides of the boxes and the sides of the furnace sections within the combustion chamber in a manner very obvious to those skilled in the art. The hollow wing arches 26 are preferably in the form of substantially rectangular boxes of metal such as cast iron of sufficient thickness to withstand the heat of the furnace without burning out, owing to the lack of presence of water therein, as is the case with the various sections 9 composing the furnace, or may be of refractory or other fire-resisting material. Of course, the bridge wall and hollow wing arches extending inwardly from the opposite sides of the furnace into the combustion chamber may be located at any place in the boiler, according to the size of the firebox which is regulated by the capacity desired or where it is necessary to block off the rear grades to reduce the capacity in long boilers when it is not necessary to use the full grate area. This, however, may be regulated according to the requirements by varying the number of sections employed.

The hollow wing arches, as previously stated, are of hollow and substantially rectangular formation but, principally, are constructed to conform to the interior of the sections of the furnace so as to overlap the joint between two sections and fit snugly between the webs of said sections as is especially shown in Fig. 1 of the drawings. In the form indicated, the top of the box is curved as indicated at 28 to conform to the curvature of the furnace sections at the top, and are closed on all sides except at the outside which is left entirely open, as indicated at 29, while the insides are provided with comparatively narrow vertical slots 30 centrally located and extending from top to bottom. By reason of the closed formation of the hollow wing arches and the flat bottom walls 31 thereof, said arches may be easily fitted in the furnace or boiler and will rest upon the bridge wall 18 without liability of displacement. Moreover, being open at the outside, the construction is cheapened owing to the casting thereof being facilitated. Furthermore, the outer sides are closed off from direct contact with the burning gases and products of combustion from the firebox, but since the hollow wing arches or boxes are of heavy metal of substantial thickness up to three-fourths of an inch or one inch or more, burning out thereof is prevented or the useful life thereof is extended for a considerable period. The cooling action caused by the contact of portions of the arches or boxes with the water-containing chambers of the furnace sections and especially the webs 24 thereof, also increases the useful life of the arches.

In order to supply auxiliary air, tubes or pipes 32 extend through sleeves 33 in the rear section 10 of the boiler and project rearwardly therefrom. These tubes extend into

the furnace through the rear or vertical portion of the combustion chamber or flue space 34, through flues or passes 35 immediately outwardly of the webs 24 at the sides of the 5 furnace sections through which fire travel of the gases and products of combustion is rearwardly from over the firebox. The inner ends of the tubes 32 are fitted in openings 36 in the rear walls of the arches 26 so that 10 auxiliary air will be drawn into or supplied to the interior of the latter highly pre-heated and escape in opposite directions toward each other through the slots 30. The slots 30 may be disposed to direct the air inwardly from the 15 sides over the bridge wall, at an angle of 90 degrees or less, and the slots may be extended inwardly at right angles to the length of sides of the furnace and the combustion chamber or passage, or at an angle as shown in 20 Figs. 3 and 5 respectively. The pipe or tube 32 may be a plain cast metal or other pipe but is preferably fluted or corrugated. In the form shown they are provided with spiral convexities, corrugations or convolutions 37 25 to cause a spiral or whirling action of the air as it passes through the same to the boxes 26 to enter into the furnace. This construction also increases the surface area of the tubes or pipes 32 with which the heated gases 30 and products of combustion come into contact, which tubes convey the auxiliary air to the boxes 26 and are exposed to the heat of 35 the furnace and products of combustion passing through the combustion space 34 after passing through the combustion space over the fire-box, over the bridge wall 18, between the hollow wing arches or boxes 26, and subsequently through the flues or flue openings 35, 20, and 21 before making its exit to the 40 chimney. By having the air tubes resting on water backed sections at one or more points helps to keep the tubes from burning out.

The rearwardly projecting ends of the 45 tubes 32 which may be corrugated spirally or otherwise, may be enlarged and are provided with valves or dampers 38 for regulating the supply of auxiliary air entering the furnace. In addition, damper arms 39 may be provided 50 on the dampers and have flexible connections or chains 40 trained over pulleys 41 and connected to an automatic pressure or temperature regulator 42 provided on the boiler or furnace for controlling the action of the 55 damper according to the steam pressure or temperature of the furnace which is set or regulated as desired. The balance beam 43 of the regulator 42, which may include a diaphragm or thermostat controlled regulator element 44 and has an adjustable weight 45 for regulating its action, as is well known in the art, may have connection through a chain or cord 46 with a draft door 47 whereby to 60 open and close the latter to automatically control the draft in proportion to the fuel

consumption or the amount of heat required. Obviously, the automatic control of the damper or valve regulating the ingress of the auxiliary air, may be associated with any automatic draft or fuel feed regulator, well known in the art, so that the auxiliary air is permitted to enter in proportion to the volume of air required for complete combustion without loss of heat and with greater efficiency owing to the complete consumption of 70 gases and the burning of the fuel employed in the furnace. By reason of the air being discharged from the elongated slots 30 above the bridge wall or baffle 18 of firebrick or other refractory material throughout the 80 height of the passage between the arches or boxes 26 between the baffle and ribs or top portion of the furnace sections, the gases and products of combustion from the burning fuel on the grate 16 are thoroughly mixed with 85 the auxiliary air to insure complete combustion and elimination of smoke passing through the flue or chimney with which the rear ends of the flues or passes 21 communicate; that is, black or carbon-containing 90 smoke, with the escaping gases and fumes.

The sectional base extension 7' is composed of two or more sections arranged against the back of the base section 7, and has top plates 7^a, the rear one 7^b of which is inclined rearwardly to an opening in the back of the section 7'. 95

The rear combustion space is open behind the bridge wall 18 and brace 19 to receive the deposit of ashes, soot, and other solid particles of combustion which slide down the inclined top plate 7^b to the rear clean-out opening which is provided with a door 7^c. This provides means for efficiently and easily 100 cleaning out the furnace, and since most of the solid particles will be deposited and removed at this point, the flues 20, 21, and 35 will require little more than dusting out. This structure also permits adjustment, i. e. 105 reduction or enlargement, of the size of the fire box and grate by using varying numbers of sections and grates 16, or different sizes of base sections 7 and 7', and varying the position of the bridge wall 18 and boxes 26 thereon, the section 7' and the wall 18 serving to 110 block off the same. This is especially desirable where the length of the boiler exceeds seventy-two inches, since restrictions are imposed especially in firing, which is by the present construction, facilitated. Where the 115 furnace or boiler has hollow water legs at the sides extending down to the floor, as is well known in the art, the fire box may be blocked off by extending the bridge wall 18 up from the floor or the base extension 7' may 120 be a metallic or brick structure.

By supplying the auxiliary air to the combustion chamber or rear space thereof directly in the path of and in a manner to intercept the burning gases and products of combus- 130

tion from the burning fuel in the fire box, directly from the atmosphere and in rear of the furnace or fire box thereof, as distinguished from in front, the same is more highly pre-heated and plentiful in oxygen to support combustion as compared with air drawn from the front, either above or below the fire box or ash pit where it is apt to be mixed with or contaminated by the partly burnt consumed gases or fumes in which the proportion of oxygen has been reduced.

While I have shown and described my invention in a preferred form, I am aware that various modifications and changes may be made without departing from the spirit of the invention, the scope of which is to be determined by the appended claims.

I claim as my invention:

1. In a boiler construction of the sectional type and each section having an inwardly projecting rib spaced from the rib of the next adjacent section, a fire box and a combustion chamber, a bridge wall between the fire box and combustion chamber and having its ends extending into the space between a pair of spaced ribs, hollow members mounted on the bridge wall and extending at their outer ends into the space between said ribs, said members disposed with their inner ends approaching the center of the bridge wall to form between said ends a restricted passage between the fire box and combustion chamber, and air supply means communicating with said hollow members and extending through the combustion chamber to communication with the outside atmosphere at the back of the furnace, said hollow members each provided with outlet means for air to direct said air into the restricted passage.
2. In a boiler construction of the sectional type, each section having an inwardly projecting rib spaced from the rib of the next adjacent section, a fire box and a combustion chamber, a bridge wall between the firebox and combustion chamber and extending into the space between a pair of ribs, members mounted on the bridge wall and interfitting at their outer ends between said ribs and forming hollow spaces between said pair of ribs, said members being disposed with their inner ends approaching the center of the bridge wall to form a restricted passage between the firebox and combustion chamber, and air supply means communicating with the hollow spaces of said members and extending to the outside atmosphere, said members being each provided with an opening at the inside to direct said air into the restricted passage.

3. In a boiler of the transverse vertical sectional type, having front, back and a plurality of intermediate sections, said intermediate sections each having a top arch portion, depending side legs and inwardly extending webs, the latter being so formed that the webs of two adjacent intermediate sections are spaced; a fire wall dividing the boiler into a front fire box and rear combustion chamber and restricting the passage vertically therebetween, side members vertically aligned with said wall and restricting said passage laterally, said side members being partially seated between and retained by the webs of two adjacent intermediate sections, said side members having air delivery openings adjacent said restricted passage; and means for supplying auxiliary air to said side members.

4. In a boiler of the transverse vertical sectional type, having front, back and a plurality of intermediate sections, the intermediate sections each having a top arch portion, depending side legs and inwardly extending webs, the webs being so formed that a space is left between the webs of two intermediate sections; a lower transverse fire wall dividing the boiler into a front fire box and a rear combustion chamber and restricting the passage vertically therebetween; side members vertically aligned with and above said fire wall and restricting said passage laterally, said side members being partially seated between and retained by the webs of two adjacent intermediate sections, said side members having air delivery openings for delivering air into the restricted passage; and means for supplying auxiliary air to said side members.

5. In a boiler of the transverse vertical sectional type having front, back and a plurality of intermediate sections, the intermediate sections having a plurality of flue openings in the upper portions thereof, and provided also with transversely extending webs and within which some of said flue openings are located; a transverse lower fire wall spaced forwardly of the rear section, side members above said fire wall and aligned therewith and extending partly between the webs of two adjacent intermediate sections, said side members having air delivery openings adjacent the restricted passage defined by said side members and fire wall; and air conductor means to said side members, said air conductor means extending through the said flue openings in the web portions of the intermediate section rearwardly of the fire wall.

THOMAS DAVID CASSERLY.
